H. D. JONES,
GAGE WHEEL FOR SCARIFYING DEVICES,
APPLICATION FILED SEPT. 13, 1920.

1,388,648.

Patented Aug. 23, 1921.

FIG. 1

FIG. 2

Henry D. Jones ^{Inventor}

By Staley & Bowman

Attorneys

UNITED STATES PATENT OFFICE.

HENRY D. JONES, OF SPRINGFIELD, OHIO, ASSIGNOR TO THE BUFFALO-SPRINGFIELD ROLLER COMPANY, OF SPRINGFIELD, OHIO, A CORPORATION OF OHIO.

GAGE-WHEEL FOR SCARIFYING DEVICES.

1,388,648.

Specification of Letters Patent. Patented Aug. 23, 1921.

Application filed September 13, 1920. Serial No. 410,069.

To all whom it may concern:

Be it known that I, HENRY D. JONES, a citizen of the United States, residing at Springfield, in the county of Clark and 5 State of Ohio, have invented certain new and useful Improvements in Gage-Wheels for Scarifying Devices, of which the following is a specification.

This invention relates to improvements 10 in scarifying devices of the kind which are attached to the rear end of road engines, it relating more particularly to a novel construction of gage wheel for use in connection with such devices.

15 One of the objects of my invention is to provide a gage wheel so constructed and associated with the scarifying tools as to prevent clogging of the road material, earth or trash between the wheel and the adjacent 20 tool.

A further object of my invention is to provide a gage wheel so constructed as to obviate side strain upon the parts.

In the accompanying drawings:—

25 Figure 1 is a rear view of so much of a road engine and the scarifying devices as is necessary to illustrate the invention, showing my improved gage wheel applied thereto.

30 Fig. 2 is a vertical section of one of the gage wheels.

The scarifying devices which I have shown are constructed substantially like the scarifier illustrated in my prior Patent No. 1,226,528 35 dated May 15, 1917. The scarifier devices are attached to the rear end of the tank 1 of the engine by providing a frame consisting of the upright supporting members 2 and 3 bolted or otherwise firmly secured to the tank. The lower end of this frame has 40 bearings 4 in which is journaled a draft bar 5 to which are keyed a series of tool holders 6, to the rear free end of which are clamped the ground breaking tools 7. Connected 45 with each of the tool holders 6, at points adjacent the rear end thereof is a shaft 8 which projects laterally beyond the series of tools at each side of the machine and has journaled thereon gage wheels 9. A 50 fluid pressure cylinder 10 has its upper end pivoted on a shaft 11 supported by the upper end of the frame members 2 and 3 and the piston rod 12 of the piston of this cylinder is connected to a yoke-shaped member 13 55 journaled on the shaft 8 so that the scarify-

ing devices may be raised and lowered and pressure applied thereto in the manner described in my prior patent referred to.

In the use of such devices, difficulty has been encountered with trash, such as the 60 hard surface of roads, lumpy earth, or other substances encountered, accumulating between the gage wheel and the adjacent tool when the gage wheel is constructed in the usual and ordinary manner such as shown 65 in my prior patent referred to. Further, these gage wheels as heretofore constructed are the cause of considerable side strain upon the parts, particularly when the machine is making turns or being moved 70 diagonally across the road, which has resulted in straining the tank to such an extent as to cause it to leak as well as bringing undesirable strain upon the operating parts. To obviate these difficulties I have 75 constructed each of the gage wheels as follows:—

The hub 14 of the wheel is connected to the inside edge of the tread 15 thereof by a web portion 16. This web portion 16 connects with the hub at a point adjacent its inner end and projects inwardly toward the center of the wheel so that the outer portion thereof will connect with the tread 15 at a point which will be substantially on a line 80 with the center of the hub so that the web projects at an angle outwardly away from the adjacent scarifying tool so as to form in effect with the tool an outwardly flaring throat. As a result of this construction the 85 trash which is encountered between either one of the gage wheels and its adjacent tool will be allowed to escape freely from between the same, being assisted in this respect by the rotation of the gage wheel. 90

The respective edges of the tread portion 15 of each gage wheel are formed on the arc of a circle or rounded, as indicated at 15^a and 15^b, as a result of which the wheels are permitted to more readily ride out of ruts 100 and depressions encountered and thus obviate to a large extent side strain upon the parts.

The hub, tread, and web are all preferably formed integrally and a series of webs 17 105 are preferably provided for strengthening purposes.

Having thus described my invention, I claim:—

1. In a scarifying apparatus, a series of 110

- scarifying tools, gage wheels associated therewith, the side of each wheel being inclined outwardly away from its adjacent tool, for the purpose specified.
5. 2. In a scarifying apparatus, a series of pivotally supported tools, gage wheels connected with said tools, one at each end of the series thereof, each gage wheel being provided with a web portion which is inclined outwardly away from its adjacent tool, for the purpose specified.
3. In a scarifying apparatus, a scarifying tool, a gage wheel adjacent thereto, said gage wheel having a hub and a tread portion, a web connecting the same, said web being connected with said hub at a point adjacent its inner end and extended out-
- wardly at an angle and being connected with the tread portion at the inner edge thereof on a line substantially midway the center 20 of the hub.
4. In a scarifying apparatus, a scarifying tool, a gage wheel adjacent thereto, said gage wheel having a tread formed with rounded edges and the side of said wheel 25 adjacent said tool being inclined outwardly and away from said tool, for the purpose specified.

In testimony whereof, I have hereunto set my hand this 4th day of September, 1920. 30

HENRY D. JONES.

Witness:

CHAS. I. WELCH.
